UNITED STATES PATENT OFFICE.

EUGENE PRINGLE, OF GLOVERSVILLE, NEW YORK.

SEPARABLE BUTTON FOR GLOVES.

SPECIFICATION forming part of Letters Patent No. 351,887, dated November 2, 1886.

Application filed December 29, 1885. Serial No. 186,981. (No model.)

To all whom it may concern:

Be it known that I, EUGENE PRINGLE, a citizen of the United States, residing at Gloversville, in the county of Fulton and State of New York, have invented certain new and useful Improvements in Separable Buttons for Gloves, Boots, &c., of which the following is a specification.

My invention relates to certain improvements in buttons for gloves, boots, &c., which will be hereinafter particularly described, and specifically set forth in the claims.

The objects of my invention are to produce small buttons for gloves and boots which will have their parts separable, and be cheaply produced and be readily applied to the articles they are to be used with, and also be strong and reliable, and capable of being attached by simple pressure of the head portion on the stud, and detached by simply pulling the head portion outwardly from the stud. I attain these objects by the means illustrated in the accompanying drawings, forming a part of this specification, in which—

Figure 1 is a sectional elevation of the button on an enlarged scale. Fig. 2 is a plan view of the head-shell of the button. Fig. 3 is a plan view of the bottom closing-piece of the button. Fig. 4 is a plan view of the catch-spring. Fig. 5 is a plan view of the head-shell support, viewed from its lower side. Figs. 6, 7, 8, 9, and 10 are views of the attaching-stud, and illustrate several modifications of the attaching bases of the same. Figs. 11 and 12 are modifications of stem and attaching base of the stud. Fig. 13 is a sectional view of a button having a modified form of head-shell support. Fig. 14 is a sectional view, commercial size, of my improved button; and Fig. 15 is a sectional view of the stud of the same.

The same letters refer to like parts throughout the several views.

In the drawings, A is the shell-head of the button, which head is made with a shell form, and having its top *a* made crowning from the annular flat portion *a'*, which latter operates as a seat for receiving the force of the tool employed to set the pieces of the button together. The side *a'* of this shell-head is extended down

from flat shoulder *a'*, and has its flange-rim *a*³ clinched on the outer margin of closing-piece B, which is made with a shell form and of a single piece, and includes the upturned flange-rim *b*, horizontal body *b'*, and central tube, *b*². The flange-rim *b* is made with a diameter corresponding with that of the inner side of side walls, *a*², of shell-head A, and is extended above the horizontal body *b'* to a distance above the clinched flange-rim *a*³, so as to bring its edge *b*³ up to the lower side of the flat portion or shoulder *a'* of shell-head A. The upper portion, 1, of the central tube, *b*², is made with a uniform thickness, and its lower end portion is made with the tapering form 2, running down from the termination of the uniformly-thick portion 1 to a knife-like edge, as shown.

C is the clinching washer, made preferably with the form shown, and having its central perforation made with a diameter about equal to that of the tube at a point above knife-edge 70 end, so as to readily slip on the same to a short distance without force, while with force it can be set up to the upper end of the taper 2, when the tapering end of the tube will be clinched on it and hold secure with the leather or fabric 75 through which the tube *b*² passes.

D is the catch-spring, which is made of a single piece of spring-wire bent in the form shown, and so as to produce the hoop or ring *d* and catching bar or arm *d'*. This ring or hoop *d* is made to have the form of the line of the side wall, *b*, of closing-piece B, and a diameter corresponding with the diameter of said wall, inside measure. The catching-arm *d'* is made to extend inwardly from 85 its point of union with ring *d* in a straight line to terminate near the opposite side of the same, and is so arranged in relation to the line of the circle of said ring as to be at one side of the median line *x* of the same, and yet relatively within the line of the circumference of the bore 3 of tube *b*² of the closing-piece B, as indicated by full and dotted lines in Figs. 4 and 5, so as to cross a side portion of said bore when the spring is in place within 95 the chamber of the closing-piece B.

E is a shell-form support interposed between closing-piece B and shell-head A. This

support is shown in Figs. 1 and 5 to have its top portion, e , made crowning to correspond with the crowning line of piece A, and its side wall e' is shown to be made with a diameter about equal to the inside diameter of ring d of the catch-spring D, so that the latter will lay all around side wall e' of this support E, as indicated by dotted lines in Fig. 5, and be readily received between said side wall e' and side wall b of piece B, as shown in Fig. 1. From the top of this arch shell or support E is projected downwardly the central tubular wall, e^2 , having its diameter of bore a little greater than that of the bore-tube portion b^2 of the bottom closing-piece, B, and also having its length to correspond with the height of the chamber between the closing-piece B and head-shell A, so that said tubular wall e^2 will be supported by said piece B at the line of union of tube b^2 with the horizontal portion b , while the upper end of this wall e^2 will give support to the crown of shell-piece A. In the edge of side wall e' of this piece E is made notch e^3 , and the lower end of tubular wall e^2 is also provided with a notch, e^4 , which is formed by removal of a portion of said end, as shown in Figs. 1 and 5. These notches e^3 e^4 receive catching-arm d' of catch-spring D, as shown by full lines in Fig. 1 and dotted lines in Fig. 4. In Fig. 13 this supporting-piece E is shown to be a plain tube between pieces A and B.

When pieces A, B, D, and E are arranged together and secured as shown in Fig. 1, the catch-spring D will be held from shifting, and the portion 3 of arm d' will be relatively over the bore of the central hole of the bottom closing-piece, while portions 4 and 5 will have support on the horizontal portion b of the same, as illustrated by full and dotted lines in Fig. 5.

F is the attaching-stud, which is connected with any suitable form of base, F'. This stud is made with any suitable form of cylindrical stem f , provided at its upper end with semi-spherical head f' and annular concave shoulder f^2 at the point of union of said head with the stem. The head f' of this stem is made with a diameter corresponding with the bore of the central tube, b^2 , so as to be readily entered into the same. This stud is set relatively at an angle with the horizontal-plane of attaching-base F', and in such a manner that the upper end will be inclined in a direction opposite to the direction of line of the pull on the stud, as indicated by arrows in Figs. 1, 7, and 15.

The attaching-bases F' can be made with any of the forms of construction shown in Figs. 6, 7, 8, 9, 10, 11, and 12, as may be selected, and with them any well-known devices—such as eyes, perforations, clinching-spurs, wire clips, or eyelets—can be employed, as may be preferred.

In some cases I omit the support E, but in best classes of buttons I would use that piece.

When the button is attached to one lap of

the glove or boot and stud F is attached to the other lap, the operator, to connect the button with the stud, will simply pass the button over the head of the stud and toward its base until the head has fully entered into the central opening, as indicated by dotted lines in Fig. 1, when the upper passage of said head will crowd against spring-arm e' of spring E, and press it outward until it has fully passed above said arm, when the latter will spring back and engage with the shoulder f^2 of the stud and be securely held. When the button is pulled in direction about on a line of the axis-tube b^2 , it will readily be drawn from the stud, the arm e' of the spring yielding before the force of the pull to slip its hold with the head of the stud; but any pull in direction at an angle to the axis of the button will be ineffectual for detaching the parts. By the inclination of the angle of the stem of the stud, as shown, the pull of the button on the stem of the stud operates with the incline to draw the button downward toward the base of the stem.

By my above-described improvements buttons of small diameter—say five-sixteenths of an inch, outside measure—can be readily produced, and be employed with gloves, boots, and other articles of wear which require small buttons, while the expense attending the manufacture of this class of buttons will be materially reduced.

Having described my invention, what I claim, and desire to secure by Letters Patent, is—

1. In a button for gloves, boots, &c., the combination, with a button-head having its bottom closing-piece, B, made with upturned flange b and downwardly-projected tube b^2 , of the catching-spring D, composed of the ring portion d , which is supported by said flange, and catching-arm d' , supported on the upper horizontal surface of said closing-piece and over one side of the upper open end of the bore of said tube for operations with the stud, substantially as and for the purposes set forth.

2. In a button for gloves, boots, &c., the combination, with head-shell A, bottom closing-piece B, and catch-spring D, of supporting device E, provided with notch e^4 and arranged between said pieces A and B, substantially as and for the purposes set forth.

3. In a button for gloves, boots, &c., the stud F, provided with an attaching-base, F', and having its stem f inclining upwardly and relatively toward or over the attaching-base and in a direction in opposition to the line of draft on said stud, substantially as and for the purposes set forth.

4. In a separable button having its head part A B provided with a stud-receiving opening, and a spring-catch which is arranged in relation to said opening, as above described, the combination therewith of stud F, provided with catching-head f' , and having its stem set in an inclined position in relation to its con-

nected attaching-base F', substantially as and for the purposes and operations set forth.

5. In combination with a button composed of the head-shell A, bottom closing-piece, B, provided with a central opening, and a catch-spring arranged relatively over a side portion of said central opening, of stud F, made with

and set relatively at one side or end of a base provided with an attaching device, substantially as and for the purposes set forth.

EUGENE PRINGLE.
